(57) **CLAIM**

The ornamental design for a massage appliance as shown and described.

DESCRIPTION

FIG. 1 is a front top perspective view of a massage appliance showing my new design;

FIG. 2 is a front bottom perspective view of the design shown in FIG. 1;

FIG. 3 is a front elevational view of the design shown in FIG. 1, the rear elevational view being a mirror image thereof;

FIG. 4 is a top plan view of the design shown in FIG. 1; and, FIG. 5 is a bottom plan view of the design shown in FIG. 1. The broken lines shown are for the purpose of illustrating portions of the massage appliance, which form no part of the claimed design.

1 Claim, 5 Drawing Sheets
